CLAIM

The ornamental design for a housing for interface module, substantially as shown and described.

DESCRIPTION

FIG. 1 is a top view of the housing for interface module, showing our new design;

FIG. 2 is a front view thereof;

FIG. 3 is a side view thereof;

FIG. 4 is a perspective view thereof;

FIG. 5 is a view opposite that shown in FIGS. 3 and 4; and

FIG. 6 is a rear view thereof.

FIG.1

FIG.2

FIG.3

FIG.4
